(57) **CLAIM**

The ornamental design for a shaver, as shown and described.

DESCRIPTION

FIG. 1 is first perspective view of a shaver showing my new design;

FIG. 2 is second perspective view thereof;

FIG. 3 is third perspective view thereof;

FIG. 4 is an exploded perspective view thereof.

FIG. 5 is a front elevational view;

FIG. 6 is a rear elevational view thereof;

FIG. 7 is a left elevational view thereof;

FIG. 8 is a right elevational view thereof;

FIG. 9 is a top plan view thereof;

FIG. 10 is a bottom plan view thereof; and,

FIG. 11 is an enlarged view of portion of FIG. 4.

The evenly spaced broken lines illustrate portions of the shaver. The dash-dot-dash broken lines illustrate the boundary of the enlarged portion of the shaver. Neither of the broken line disclosures form part of the claimed design.
